UNITED STATES PATENT OFFICE.

HARRY BARLOW AND JOHN E. HENRY MATHIES, OF EAST MOLINE, ILLINOIS.

MAIL-BAG DELIVERY AND RECEIVING CRANE.

Application filed January 28, 1922. Serial No. 532,453.

To all whom it may concern:

Be it known that we, HARRY BARLOW and JOHN ERNEST HENRY MATHIES, citizens of the United States, residing at East Moline, in the county of Rock Island and State of Illinois, have invented certain new and useful Improvements in Mail-Bag Delivery and Receiving Cranes, of which the following is a specification, reference being had

10 to the accompanying drawings.

The purpose of the present invention is to provide a mail bag delivery and receiving crane for use in connection with mail cars, and which is adopted to be reciprocated laterally through the side door of a mail car, for the purpose of delivering and receiving a mail bag.

Another purpose is the provision of a crane comprising a reciprocating rod having an angle rod secured to its extremity, with one arm of the angle rod extending rearwardly, together with a guard plate, which has rearwardly extending ears to engage and prevent a metallic loop carried by

25 the mail bag from swinging laterally.

Still another purpose is the provision of a spring tensioned member hingedly mounted on the guard plate, to hold the metallic loop of the mail bag against the guard plate, said spring tensioned member adapted to be tilted, due to the metallic loop of the mail bag bearing against it as it is removed therefrom by the receiving crane which is disposed at the side of the station.

35 A further purpose is the provision of means on the reciprocating rod of the delivering crane on the mail car, to receive the mail bag from a delivering mechanism at the station and which is similar to that carried by the mail car.

A still further purpose is the provision of a mail bag receiving bracket on the crane at the station, to receive a mail bag from the delivering mechanism of the car.

45 While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features

55 and combination of parts, as will be herein-

after set forth, shown in the drawings and claimed.

In the drawings:

Figure 1 is a view in side elevation of a conventional form of mail car, showing the mail bag delivery and receiving crane in the act of passing a similar apparatus at the station, for the exchange of mail bags as the train passes;

Figure 2 is a vertical sectional view on line 2—2 through the mail car, showing the crane as projecting through the door opening in full lines, and positioned within the car in dotted lines;

Figure 3 is an enlarged detail view of the mail bag holding and delivering device of the reciprocating crane which is carried by the mail car;

Figure 4 is a rear view;

Figure 5 is a vertical sectional view 75 through Figure 4, showing the spring tensioned clamp as having been moved rearwardly and the metallic loop of the mail bag in the act of leaving the arm which acts to support the loop;

Figure 6 is a view of the receiving arm of the crane which is carried by the mail car; and

Figure 7 is a detail perspective view of the receiving arm which is carried by the crane at the side of the station.

Referring to the drawings, 1 designates a conventional form of mail car, and secured to the under face of the roof thereof are brackets 2, which have circular supports or bearings 3, in which a tubular guide 4 is mounted. The bearings or supports have depending parts 5, in which rollers 6 are mounted upon the pins 7. The rollers 6 are aligned with an elongated slot 8 which is formed in the tubular guide.

Mounted in the tubular guide is a rod 9, preferably tubular, and is adapted to ride upon the rollers 6, so that it may be reciprocated or projected laterally through the door opening 10 of the car when it is desired to deliver and receive the mail bag. Obviously after the mail bag has been delivered, and another received, the rod or crane may be receded within the car, carrying the mail bag (which may be received thereon) into the interior of the car. Projecting downwardly from the rod or crane arm 9 is a handle 11, the shank of which projects through the slot 8, and due to the shank of the handle

100

105

110

projecting through the slot, the rod or crane arm 9 is guided in its movements. Furthermore the rod or crane arm 9 is prevented from rotating, especially when in the act of 5 delivering and receiving a mail bag.

Mounted upon the outer end of the rod or crane arm 9 is a collar 12, and projecting through the collar transversely thereof and through the rod 9 is one arm 13 of an angle 10 rod 14. The other arm 15 of the angle rod extends rearwardly and slightly downwardly, so as to permit the metallic loop 16 of the mail bag 17 to be easily disengaged therefrom. The arm 13 of the angle rod has 15 on its upper end a nut 18, to not only secure the angle rod in place, but also to hold the collar 12 in position.

A plate 19 is connected rigidly to the collar 12, and the lower portion of the plate 19 20 is relatively broad and has depending arms 20, which straddle the arm 15 of the angle rod, thereby holding the metallic loop 16 of the mail bag in a position on the arm 15, whereby it may be easily removed, when in 25 the act of delivering the bag. The outer edges of the arms 20 have rearwardly extending ears 21, which are positioned relatively to the arm 15 of the angle rod 14, so as to engage the sides of the elongated 30 metallic loop 16 of the mail bag, thereby preventing the metallic loop 16 from rocking on the arm 15, due to the vibrations of the car.

The plate 19 is provided with ears 22, for 35 the reception of a hinge pin 23, which in turn engages in the ears 24 of the angle clamp 25. This angle clamp 25 also has depending arms 26 corresponding to the depending arms 20 of the plate 19. The arms 40 26 are positioned between the rearwardly extending ears 21, and act to clamp the metallic loop of the mail bag against the plate 19. The clamp 25 is angular as shown, and its arm 27 is provided with an aperture 28, through which a curved guide rod 29 engages. This curved guide rod 29 is carried 45 by an upstanding part 30 of the plate 19. A coil spring 31 engages the guide rod (which is concentric with the hinge of the clamp), and is interposed between the upstanding part of the plate 19 and one arm of the clamp, thereby holding the depending arms of the clamp against the metallic loop of the mail bag, so as to hold it against the 50 plate 19. The rearwardly extending ears act to prevent rocking of the metallic loop of the mail bag, even though the bag itself is suspended from the lower end of the loop. An arm 32 is fixedly carried by the angle 55 clamp 25, and is adapted for opening the clamp 25 when it is desired to attach the metallic loop 16 of a mail bag on the arm 15.

A collar 33 is carried by the rod 9, and projecting through the collar 33 and 60 65 through the rod is an arm 34, having a nut

on one end to not only hold the arm in place, but also to hold the collar in place, since the arm penetrates through the collar.

Mounted at the side of the platform at the station is an upstanding support 35 constituting a mail bag receiving and delivering crane, and projecting from the support is a crane arm 36, which corresponds to the rod 9 which is carried by the car. This crane arm 36 carries a mail bag delivering 70 75 apparatus, which is similar in every respect to the mail bag delivering device carried by the arm 19 of the mail car.

However the arm 27 of the angle clamp 25 of the delivery apparatus at the side of the 80 station is extended as shown in Figure 1 constituting a handle, for opening the angle clamp of the delivery apparatus at the station. Also the arcuate rod 29 of the delivery 85 apparatus at the station is carried by the arm 27, and works through an opening or aperture 28 of the upstanding part 30 of the plate 19. By these mechanisms the delivery of mail bags is effected when the train passes 90 the station.

A collar 37 is mounted upon the vertical support of the crane at the station, and engaging through the collar 37 is an arm 38 of an angle rod 39. Where the rearwardly extending arm of the angle rod joins the 95 lateral arm thereof braces 40 and 41 are connected, the former receives and is connected to a forwardly projecting arm of the angle rod 39 by means of a nut 42, while the latter brace extends downwardly and laterally and is connected at 43 to the upright portion of the crane. A transverse rod 44 is secured to the angle rod 39, and acts to engage the metallic loop of the mail bag, to assist materially in pulling or detaching the loop 100 from the delivering mechanism of the mail car.

When exchanging mail bags at the station, as the train is rapidly passing, it will be noted that a mail bag is suspended from each of the delivering devices. The rod or crane 9 of the mail car is projected through the door opening, sufficiently to permit the angle rod of the crane at the station to pass through the loop of the mail bag. In doing 110 this the arm (which passes through the loop of the mail bag at the station) on the rod 9 is positioned so that it will pass through the metallic loop of the mail bag at the station at the same time the arm of the crane 115 at the station passes through the metallic loop of the mail bag on the car. Simultaneously the angle clamps are caused to open, against the action of the springs, thereby causing a delivery and receiving of the mail 120 bag, as the train passes.

It will be noted that the bottom or closed end of each mail bag has riveted thereto an elongated metallic strap 45, which carries an eye 46, which is in turn connected to the 130

elongated metallic loop 16, which is designed to be connected to the delivering mechanism of the car, or that at the station. It is the aim to utilize metallic loops on the mail bag 5 and also the elongated plate for the purpose of eliminating wear upon the sacks or bags, since the bags are simply suspended instead of being stretched on the crane. Obviously when the rings and plates of the mail bag 10 wear out, they may be very readily replaced.

The invention having been set forth, what is claimed is:—

1. In a mail bag delivery apparatus, the combination with a crane arm, of a collar 15 engaged with the outer end thereof, means passing through the collar and through the arm to hold the collar in place, and provided with a rearwardly extending projection, a guard plate secured to the collar and 20 provided with means engageable upon opposite sides of the metallic loop of a mail bag, to hold said loop on said rearwardly extending projection, so as to prevent the loop from rocking, and a spring tensioned angle clamp- 25 ing plate hingedly mounted upon the guard plate and bearing upon the metallic loop for holding it against the guard plate.

2. In a mail bag delivery apparatus, the combination with a crane arm, of a collar 30 engaged with the outer end thereof, means passing through the collar and through the arm to hold the collar in place, and provided with a rearwardly extending projection, a guard plate secured to the collar and 35 provided with means engageable upon oppo-

site sides of the metallic loop of a mail bag, to hold said loop on said rearwardly extending projection, so as to prevent the loop from rocking, and a spring tensioned angle clamp hingedly mounted upon the guard 40 plate and bearing upon the metallic loop for holding it against the guard plate, said angle clamp having depending arms straddling said rearwardly extending projection, for holding the metallic loop flat against the 45 guard plate.

3. In a mail bag delivery apparatus, the combination with a crane arm, of a collar engaged with the outer end thereof, means passing through the collar and through the 50 arm to hold the collar in place, and provided with a rearwardly extending projection, a guard plate secured to the collar and provided with means engageable upon opposite sides of the metallic loop of a mail bag, 55 to hold said loop on said rearwardly extending projection, so as to prevent the loop from rocking, and a spring tensioned angle clamp hingedly mounted upon the guard plate and bearing upon the metallic loop for holding it against the guard plate, and means carried by the angle clamp and adapted to be cammed downwardly, to assist in tilting the angle clamp rearwardly, as the metallic loop is being disengaged from the rear- 60 wardly extending projection.

In testimony whereof we hereunto affix our signatures.

HARRY BARLOW.

J. E. HENRY MATHIES.
